(57) **CLAIM**

We claim the ornamental design for an LED cover mounting for refrigerator, as shown and described.

DESCRIPTION

FIG. 1 is a front perspective view of an LED cover mounting for refrigerator showing our new design;
FIG. 2 is a rear perspective view thereof;
FIG. 3 is a front elevation view thereof;
FIG. 4 is a rear elevation view thereof;
FIG. 5 is a left-side elevation view thereof;
FIG. 6 is a right-side elevation view thereof;
FIG. 7 is a top plan view thereof;
FIG. 8 is a bottom plan view thereof;
FIG. 9 is a partial enlarged view of portion 9 in FIG. 1; and,
FIG. 10 is a partial enlarged view of portion 10 in FIG. 2.
The dot-dot-dash broken lines shown in FIGS. 1, 2, 9 and 10 indicate the enlargement areas and form no part of the claimed design.
